The ornamental design for CD slot mount and holder combination for mobile devices, as shown and described.

DESCRIPTION

FIG. 1 is a front isometric view of a CD slot mount and holder combination for mobile devices showing our new design;

FIG. 2 is a front view of a CD slot mount and holder combination for mobile devices showing our new design; FIG. 3 is a rear view of a CD slot mount and holder combination for mobile devices showing our new design; FIG. 4 is a right side view of a CD slot mount and holder combination for mobile devices showing our new design; FIG. 5 is a left side view of a CD slot mount and holder combination for mobile devices showing our new design; FIG. 6 is a top view of a CD slot mount and holder combination for mobile devices showing our new design; FIG. 7 is a bottom view of a CD slot mount and holder combination for mobile devices showing our new design; FIG. 8 is a front isometric view of a CD slot mount and holder combination for mobile devices showing our new design with the holder's arm extended;

FIG. 9 is a front view of a CD slot mount and holder combination for mobile devices showing our new design with the holder's arm extended;

FIG. 10 is a rear view of a CD slot mount and holder combination for mobile devices showing our new design with the holder's arm extended;

FIG. 11 is a right view of a CD slot mount and holder combination for mobile devices showing our new design with the holder's arm extended;

FIG. 12 is a left view of a CD slot mount and holder combination for mobile devices showing our new design with the holder's arm extended;

FIG. 13 is a top view of a CD slot mount and holder combination for mobile devices showing our new design with the holder's arm extended;

FIG. 14 is a bottom view of a CD slot mount and holder combination for mobile devices showing our new design with the holder's arm extended;

FIG. 15 is a front isometric view of a CD slot mount for the CD slot mount and holder combination for mobile devices showing our new design;

FIG. 16 is a front view of a CD slot mount for the CD slot mount and holder combination for mobile devices showing our new design;

FIG. 17 is a rear view of a CD slot mount for the CD slot mount and holder combination for mobile devices showing our new design;

(Continued)

FIG. 18 is a left side view of a CD slot mount for the CD slot mount and holder combination for mobile devices showing our new design;

FIG. 19 is a right side view of a CD slot mount for the CD slot mount and holder combination for mobile devices showing our new design;

FIG. 20 is a top view of a CD slot mount for the CD slot mount and holder combination for mobile devices showing our new design;

FIG. 21 is a bottom view of a CD slot mount for the CD slot mount and holder combination for mobile devices showing our new design;

FIG. 22 is a front isometric view of a CD slot mount for the CD slot mount and holder combination for mobile devices, with the back fins twisted for different fitting to the vent, showing our new design;

FIG. 23 is a front view of a CD slot mount for the CD slot mount and holder combination for mobile devices, with the back fins twisted for different fitting to the vent, showing our new design;

FIG. 24 is a rear view of a CD slot mount for the CD slot mount and holder combination for mobile devices, with the back fins twisted for different fitting to the vent, showing our new design;

FIG. 25 is a left side view of a CD slot mount for the CD slot mount and holder combination for mobile devices, with the back fins twisted for different fitting to the vent, showing our new design;

FIG. 26 is a right side view of a CD slot mount for the CD slot mount and holder combination for mobile devices, with the back fins twisted for different fitting to the vent, showing our new design;

FIG. 27 is a top view of a CD slot mount for the CD slot mount and holder combination for mobile devices, with the back fins twisted for different fitting to the vent, showing our new design;

FIG. 28 is a bottom view of a CD slot mount for the CD slot mount and holder combination for mobile devices, with the back fins twisted for different fitting to the vent, showing our new design;

FIG. 29 is a front isometric view of a holder for the CD slot mount and holder combination for mobile devices showing our new design;

FIG. 30 is a front view of a holder for the CD slot mount and holder combination for mobile devices showing our new design;

FIG. 31 is a rear view of a holder for the CD slot mount and holder combination for mobile devices showing our new design;

FIG. 32 is a left side view of a holder for the CD slot mount and holder combination for mobile devices showing our new design;

FIG. 33 is a right side view of a holder for the CD slot mount and holder combination for mobile devices showing our new design;

FIG. 34 is a top view of a holder for the CD slot mount and holder combination for mobile devices showing our new design;

FIG. 35 is a bottom view of a holder for the CD slot mount and holder combination for mobile devices showing our new design;

FIG. 36 is a front isometric view of a holder for the CD slot mount and holder combination for mobile devices showing our new design, with the holder's arm extended;

FIG. 37 is a front view of a holder for the CD slot mount and holder combination for mobile devices showing our new design, with the holder's arm extended;

FIG. 38 is a rear view of a holder for the CD slot mount and holder combination for mobile devices showing our new design, with the holder's arm extended;

FIG. 39 is a right side view of a holder for the CD slot mount and holder combination for mobile devices showing our new design, with the holder's arm extended;

FIG. 40 is a left side view of a holder for the CD slot mount and holder combination for mobile devices showing our new design, with the holder's arm extended;

FIG. 41 is a top view of a holder for the CD slot mount and holder combination for mobile devices showing our new design, with the holder's arm extended; and,

FIG. 42 is a bottom view of a holder for the CD slot mount and holder combination for mobile devices showing our new design, with the holder's arm extended.
